UNITED STATES PATENT OFFICE.

DAVID B. JOHNSON, OF LYNCHBURG, OHIO, ASSIGNOR OF ONE-FOURTH TO RAYMOND P. MURPHY AND ONE-FOURTH TO HAMER CASHATT, BOTH OF LYNCHBURG, OHIO.

MAIL-DISTRIBUTING APPARATUS.

1,251,383.

Specification of Letters Patent. Patented Dec. 25, 1917.

Application filed March 21, 1917. Serial No. 156,380.

To all whom it may concern:

Be it known that I, DAVID B. JOHNSON, a citizen of the United States, residing at Lynchburg, in the county of Highland and State of Ohio, have invented certain new and useful Improvements in Mail-Distributing Apparatus; and I do hereby declare the following to be a full, clear, and exact description of the invention, such as will enable others skilled in the art to which it appertains to make and use the same.

The invention relates to a mail distributing apparatus.

The object of the present invention is to provide a simple, practical and efficient mail distributing apparatus of strong, durable and inexpensive construction designed for the use of apartments and the like and capable of enabling a mail carrier at a single point to distribute the mail for the tenants throughout an entire apartment, thereby effecting a great saving in time and labor, and obviating the necessity of mail carriers going to the different portions of an apartment or other building.

A further object of the invention is to provide a mail distributing device of this character which will be under the control of the mail carrier and which may be readily locked in proper position to afford the various tenants of an apartment access to their respective mail boxes or receptacles, and at the same time prevent an unauthorized person from changing the mail receptacles.

With these and other objects in view, the invention consists in the construction and novel combination of parts hereinafter fully described, illustrated in the accompanying drawings and pointed out in the claims hereto appended; it being understood that various changes in the form, proportion, size and minor details of construction, within the scope of the claims, may be resorted to without departing from the spirit or sacrificing any of the advantages of the invention.

In the drawings:

Figure 1 is a front elevation partly in section of a mail distributing apparatus constructed in accordance with this invention.

Fig. 2 is a vertical sectional view of the same.

Figs. 3 and 4 are enlarged sectional views of the rotary mail holder or receptacle.

Fig. 5 is a plan view of a portion of the

same showing one of the doors of the compartments.

Fig. 6 is a detail view of the lower door of the well portion of the cabinet.

Fig. 7 is a detail sectional view on the line 7—7 of Fig. 4.

Like numerals of reference designate corresponding parts in the several figures of the drawings.

In the accompanying drawings, in which is illustrated the preferred embodiment of the invention, the mail distributing apparatus comprises in its construction a vertical casing 1 forming a well 2 and designed to be built in the wall of apartment houses and similar structures when the same is erected, but in apartments which have already been built the apparatus may be installed at the most convenient point. The vertical casing, which may be constructed of any suitable material, has mounted within it an endless carrier comprising spaced endless belts 3, upper and lower grooved wheels 4, and upper and lower transverse shafts 5 on which the grooved wheels are mounted. The endless belts may be of any desired construction and they are provided at intervals with bearing boxes 7 located at the front or outer stretch or flight of the endless belt when the apparatus is in its normal position and receiving transverse shafts 8 of rotary mail holding receptacles 9 consisting of drums having hubs 10 which are secured to the shafts by set screws 11 or other suitable fastening means. The drums correspond with the floors of the apartment and they are designed to be provided with a sufficient number of mail receiving compartments 12 of sufficient size to receive ordinary mail matter and formed by radially arranged partitions 13 extending from the hub of the drum to the periphery thereof. The periphery is formed by doors 14 preferably curved, as shown, and hinged at one side at 15 to the side or head of the drum and provided at the opposite side with a suitable locking device 16. Any number of the compartments may be provided and the doors or other portions of the compartments will be provided with suitable means for designating the number of the apartment and the name of the tenant entitled to the mail of the compartment. Also in large apartment houses or buildings the shafts may be provided with a plurality of the rotary drums 110

110

110

or receptacles so that a sufficient number of mail receiving compartments may be readily provided for each floor of an apartment house. When the drums, which are adapted to be rotated to bring any compartment to the front, are in their normal position they are located opposite doors 17 by means of which the tenants of the various floors of an apartment house may obtain access to the mail holders or receptacles, and in practice suitable means will be employed for enabling a mail carrier to lock the mail holding receptacles in such position. In the accompanying drawings an ordinary post-office padlock 18 is shown and is adapted to engage around the rim of one of the lower wheels 4 and a suitable keeper 19. This will prevent anyone from changing the position of the receptacles with relation to the doors of the casing. The casing is designed to extend from the top to the bottom of an apartment house, and while only three of the rotary mail holding receptacles are shown, the desired number will be employed, and when the endless carrier is unlocked the mail carrier may partially rotate the wheels of the endless carrier and successively bring the mail holding receptacles to the bottom of the well opposite a lower door 20 and may rotate the receptacles or holders and distribute the mail to the various tenants having the compartments of such mail holder and after such mail is distributed the next receptacle or mail holder may be brought to the bottom of the endless carrier and so on until the mail is entirely distributed. The casing is designed to be provided at the lower portion with a desk or cabinet 21, with which communicates a mail chute 22 for enabling mail from the apartment house to be delivered to the cabinet or mail box 21, which is arranged in desk form for the convenience of the mail carrier. The cabinet or desk 21 may be provided with a drawer 22^a and doors 23, suitable locking devices being of course employed. The compartments are circular shaped and they extend clear to the hub of the rotary mail

receptacles or holders, and while the latter are shown cylindrical they may be of polygonal form to provide flat doors and peripheral faces. To facilitate the ready rotation of the endless carrier the lower shaft is provided at one end with a crank 24 but any other suitable means may be employed for enabling the endless carrier to be operated. The device will enable a mail carrier to seat himself at the desk or letter box and in a comparatively short time distribute the mail throughout a large apartment house and the occupants of the apartment house will be able to obtain their mail on the same floor of their apartment at a much earlier hour and without descending to the entrance of the building. 85

What is claimed is:

1. A mail distributing apparatus including an endless carrier designed to be mounted in a well of an apartment house or the like and composed of spaced belts and wheels 70 receiving the said belts, and a plurality of rotary mail holding receptacles located between and carried by the said belts and provided with an annular series of mail receiving compartments forming individual letter 75 boxes and having individual doors and adapted to be rotated to bring the individual compartments and doors to the front or back of the apparatus.

2. A mail distributing device including an 80 endless carrier designed to be mounted in a well in an apartment house or the like and comprising spaced endless belts and wheels receiving the belts, said belts being provided at intervals with shafts, and rotary mail 85 holders mounted on the shafts and consisting of drums having radial partitions forming mail receiving compartments, said drums being also provided at their peripheries with doors for closing the said compartments. 90

In testimony whereof I affix my signature in presence of two witnesses.

DAVID B. JOHNSON.
